OTTO PETERMANN, OF NEW YORK, N. Y., ASSIGNOR, BY MESNE ASSIGNMENTS, TO CORONA TYPEWRITER COMPANY, INCORPORATED, A CORPORATION OF NEW YORK.

PLATEN-SHIFT FOR TYPE-WRITING MACHINES.

1,121,035.

Patented Dec. 15, 1914.

Application filed June 12, 1909. Serial No. 501,850.

To all whom it may concern:

Be it known that I, OTTO PETERMANN, a citizen of the Republic of Switzerland, and a resident of New York, county and State 5 of New York, have invented certain new and useful Improvements in Platen-Shifts for Type-Writing Machines, of which the following is a full, clear, and exact description.

10 This invention relates more particularly to platen shifts of foldable front strike or visible typewriting machines.

One object of the invention is to provide a simple and efficient typewriting machine 15 in which the platen carriage and other parts may be mounted upon a support and the platen carriage and support as well as the parts mounted thereon positively moved to different elevations to adapt the type heads 20 to have a plurality of characters thereon, and which support is so constructed that the platen carriage in addition to its shift movements may be folded forward over the keyboard to make the machine compact 25 when not in use to adapt the same for transportation and for other purposes.

Another object of the invention is to provide simple and efficient means whereby the carriage and support with the mechanism 30 arranged thereon may be locked in any of the shifted positions of said carriage.

A further object of the invention is to provide simple and efficient lever mechanism 35 in which the shift levers may be located on the same side of the machine, and which levers are so connected and coöperate in such a way that the platen may be elevated the proper distance for the engagement 40 of the type with the work.

With these and other objects in view, the invention will be hereinafter more particularly described with reference to the accompanying drawings, which form a part 45 of this specification, and will then be pointed out in the claims at the end of the description.

In the drawings, Figure 1 is a vertical section, partly in elevation, showing one 50 form of machine embodying the invention. Fig. 2 is a fragmentary sectional plan view taken on a line II—II of Fig. 1. Fig. 2^a is a fragmentary section, partly in eleva-

tion, showing the shift arm on the side of the machine opposite the shift levers; and 55 Fig. 3 is a fragmentary view showing how the shift levers may be assisted in elevating the carriage support and mechanism mounted thereon.

The metallic frame 10 of the machine is 60 constructed and arranged in any suitable manner, and may consist of side members, and an integral back member with an intermediate transversely-extending bar 11 suitably fastened to the sides of the frame 65 and serving as a brace therefor, and a second transverse bar 12 at the front of the machine, the whole machine frame being constructed of sheet metal with rounded edges for the purpose of making the same 70 light and strong.

The machine is provided with a platen 13, and a carriage 14 for the platen which is suitably mounted to move along a frame or support 15. The work may be guided 75 about the platen, and the platen operated for letter and line spacing in any desired manner.

To raise the carriage and platen to different elevations to adapt the type heads to 80 have a plurality of characters thereon so that each character may strike at the same point according to the elevation of the carriage and the platen carried thereby, two shift levers are provided, one for the upper 85 case and one for the figures, which are adapted to elevate the carriage and its support 15. The lever 16 is for the figures and is intended to give the greatest elevation to the carriage and support or frame 15. This 90 lever 16 has the usual finger piece, and is held to a transversely-extending rock shaft 17, which is pivotally held to the sides of the machine frame, the inner end of said lever being connected to the lower end of a 95 slide 18. There is a slide 18^a on the opposite side of the machine and this slide is connected to an arm 18^b extending from the shaft 17 to cause both slides to move in unison. These slides 18 and 18^a form a frame 100 and are held to move vertically in the brackets 19 located in the rear corners of the machine frame, and said slides may be made from sheet metal or may be made from a rod or bar, and are angularly formed so as to 105 provide extensions 20 which project forward

on opposite sides of the machine toward the key-levers. The support 15 includes arms or brackets 21 which are held to the carriage bed and are pivoted at 22 to the extensions 5 20 so that the entire weight of the carriage may rest on the angular slides 18 and 18^a of the support 15. The arms 21 with the carriage may be folded over above the finger parts of the key-levers thus making a 10 very compact machine for transportation purposes or as a convenient means to fold the work over so that it cannot be read when it is not desired to take the same out of the machine. The lever 16 carries a projection 15 23 on its inner end through which passes a pin 24 which is adjustably held in said projection and is locked thereto by the nuts 25 located on opposite sides of the projection, and said pin 24 is adapted to enter an 20 aperture 26 in the part 27 of one of the brackets 19. The lever 28 for the upper case or capitals is slotted at 29 to rest upon the rod 17, and is held to the lever 16, at 30, by means of a screw 31 which passes through 25 an elongated slot 32 in said lever 28 so that there is a limited amount of lost motion between the shift levers. The outer end 33 of the lever 28 is angularly formed to provide a cam surface 34 and is adapted to engage 30 the outer edge of a dog, stop or arm 35. This stop 35 is normally forced in one direction by a spring 36 against the action of the lever 28, and said stop is pivoted at 37 to the under surface of the bracket 19. The 35 stop or arm has an end 38, Fig. 2, adapted to be forced backward under the opening or aperture 26 in the bracket through which the pin or device 24 passes so as to close said opening and serve as a stop for the 40 lever 16, thus giving the intermediate vertical movement to the carriage and support.

Each of the shift levers 16 and 28 may be locked so as to hold the carriage in either of its vertical adjustments, and for this purpose a projection 39 is provided on the lever 28 to form a slot 40, and the lever 16 is provided with a projection 41 forming a slot 42. A lock lever 43 is pivoted to the frame of the machine and is provided with two 45 projecting portions 44 which limit the movement of said lever in either direction by engaging the inturned edge 45 of the side of the machine frame. The lock lever 43 is provided with two outwardly-extending 50 parts 46 and 47, the latter of which is adapted to engage the slot 40 and the former the slot 42 according to the lever depressed for shifting and elevating the carriage on its support.

60 It will be seen that when the lever 16 is moved downward, the inner end thereof will raise the slides 18 and thereby the platen and other mechanism mounted upon the frame 15, and in this position may be locked by 65 the lever 43. The lever 16 gives the greatest

vertical throw or elevation to the carriage and platen, and during this movement the pin 24 will enter the opening 26 of the bracket 19. If the lever 28 is moved downward, a certain amount of lost motion will take place between said lever and the shift lever 16 so that the end 34 will force the stop 35 to cause the end 38 to close the opening 26 in the bracket 19, and on further movement of said lever 28 the lever 16 will 70 be carried therewith and the two will move in unison until the pin 24 engages the stop 35, and will thereby prevent further movement of the shift levers. The lever 28 may be locked in this position so that all the key 75 levers depressed will print upper case letters. 80

The shift keys 16 and 28 may be assisted in elevating the carriage and support by a spring 48, Fig. 3, which is fastened at one end to the frame, and at its other end is held to a screw or adjusting device 49 supported in the end of a bracket 50, which bracket is held to the transverse rod or shaft 17. The tendency of the spring 48 is to force the levers downward and carriage and support upward, and the tension of the spring may be varied by adjusting the screw 49.

From the foregoing it will be seen that simple and efficient shift mechanism is provided for the carriage, support, and platen; that simple means is provided for moving the platen to different elevations and for locking the same in such positions, and that said mechanism is adapted for use in connection with various forms of typewriting machines.

Having thus described my invention, I claim as new and desire to secure by Letters Patent:—

1. In a typewriting machine, the combination with a vertically movable upper portion of the machine supporting the carriage and its operating mechanism, of a vertically movable frame supporting the said upper portion of the machine, levers located on one side of the machine and adapted to raise the upper portion of the machine to different elevations, and a horizontally movable and pivoted stop normally held against action when one of the levers is depressed but which is actuated by the other lever to limit the movement thereof and thereby impart relatively different throws to the carriage and upper portion of the machine.

2. In a typewriting machine, the combination with a vertically movable upper portion of the machine supporting the carriage and its operating mechanism, of a vertically movable frame supporting the said upper portion of the machine, levers located on one side of the machine and adapted to raise the upper portion of the machine to different elevations, and a horizontally movable and pivoted stop normally held against

action when one of the levers is depressed but which is actuated by direct engagement with the other lever and limits the movement thereof.

5. In a typewriting machine, the combination with a vertically movable upper portion of the machine supporting the carriage and its operating mechanism, of a vertically movable frame supporting the said 10 upper portion of the machine, a pair of shift levers connected with said vertically movable frame and located on one side of the machine, said levers being adapted to raise the upper portion of the machine to 15 different elevated positions, said shift levers being provided with slots, and a pivoted locking lever having projections adapted to engage either or both of said levers to hold the upper movable portion of the machine 20 in its elevated positions.

4. In a typewriting machine, the combination with a vertically movable upper portion of the machine supporting the carriage, of a vertically movable frame supporting the said upper portion of the machine, and a pair of shift levers connected with said vertically movable frame and located on one side of the machine, said levers being adapted to raise the upper portion of 25 the machine to different elevated positions, and being provided with slotted projections, and movable means having projections adapted to engage either or both of said levers to hold the upper movable portion of 30 the machine in its elevated positions.

5. In a typewriting machine, the combination with a vertically movable frame mounted in the main frame of the machine, of a frame mounted on said vertically movable frame and supporting the traveling carriage and platen, a rotary transverse shaft mounted in the main frame of the machine, a lever held to said shaft and pivoted at its inner end to the vertically movable 45 frame, a second lever connected to said first-mentioned lever and having a pivotal connection with said rotary shaft, and a laterally movable stop adapted to be operated by the second lever and moved into position to 50 limit the throw of the first lever.

6. In a typewriting machine, the combination with a vertically movable frame mounted in the main frame of the machine, of a transverse shaft mounted in the main 55 frame of the machine, a shift lever held to said shaft and held at its inner end to the vertically movable frame, a second lever connected to said first-mentioned lever and having a pivotal connection with said shaft, and a laterally movable stop adapted to be operated by the second lever and moved into position to 60 limit the throw of the first lever.

7. In a typewriting machine, a vertically movable frame mounted in the main frame 65 of the machine, a frame mounted upon the

said vertically movable frame and supporting the carriage and platen, a pair of levers having independent operating means, one of said levers being attached to the vertically movable frame in the main frame of 70 the machine and adapted to raise it to elevated position, a second lever connected to said first lever and coöperating with said first lever to raise the vertically movable frame, and a pivoted dog movable by one of 75 the levers for limiting the coöperative movement of said levers.

8. In a typewriting machine, the combination with a vertically movable support mounted in the main frame of the machine, 80 of a carriage and platen carried by said support, a pair of levers located at one side of the main frame of the machine and having independent operating keys, one of said levers being held to the vertically movable 85 support in the main frame of the machine and adapted to raise it to an elevated position, a second lever connected to said first lever and coöperating with said first lever to raise the vertically movable support, and a pivoted stop for limiting the coöperating 90 movement of said levers.

9. In a typewriting machine, the combination with a carriage, of a pair of shift levers adapted to move the carriage to different elevated positions, a bracket having an opening therein, a pin carried by one of the levers and adapted to enter said opening, and a laterally movable pivoted stop adapted to be forced in position to close the opening 100 to limit the throw of said pin carrying lever.

10. In a typewriting machine, the combination with a carriage, of a pair of shift levers adapted to move the carriage to different elevated positions, a bracket having an opening therein, a pin carried by one of the levers and adapted to enter said opening, and means adapted to be forced in position 105 to close the opening to limit the throw of said pin carrying lever.

11. In a typewriting machine, the combination with a carriage, of a pair of shift levers having independent operating means adapted to move the carriage to different elevated positions, and a horizontally movable and pivoted stop operated by one of the levers only to limit the vertical movement 115 of the carriage by said lever.

12. In a typewriting machine, the combination with a carriage, of a pair of shift levers having independent operating keys located on the same side of the machine and adapted to move the carriage to different elevated positions, and a movable and pivoted stop independent of said levers and operated by one of the levers only to limit the vertical movement of the carriage by said lever.

13. In a typewriting machine, the combi- 130

19. In a typewriting machine, the combination of a carriage, a transversely extending rotary rod, a shift lever held to said rod and connected at its inner end to move the carriage, a second lever pivotally held to said rod and having a loose connection with the first-mentioned lever to have a limited movement independent thereof, a stop adapted to be operated by said second lever to engage a part carried by the first-mentioned lever to limit the movement thereof, and an arm held to the rod and connected to the carriage at the side of the machine opposite the first-mentioned lever. 70
20. In a typewriting machine, the combination of a carriage, a transversely extending rod, a shift lever held to said rod and connected at its inner end to elevate the carriage, a second lever having a pivoted connection on said rod and provided with a loose connection with the first-mentioned lever to have a limited movement independent of said first-mentioned lever, said second lever having a cam edge, a support provided with an opening, a stop pivotally held to said support and adapted to be engaged by the cam end of said second lever and adapted to be moved thereby to close the opening in the support, a spring tending normally to force the stop against the action of the lever, and a pin carried by the first-mentioned lever and adapted to enter the opening when the first-mentioned lever is depressed. 80
21. In a typewriting machine, the combination of a carriage, a transversely extending rod, a shift lever fixed to said rod and connected at its inner end to elevate the carriage, a second lever having a pivoted connection on said rod and provided with a loose connection with the first-mentioned lever to have a limited movement independent of said first-mentioned lever, a support provided with an opening, and a stop pivotally held to said support and adapted to be engaged by the end of said second lever and adapted to be moved thereby to close the opening in the support. 90
22. In a typewriting machine, the combination of a carriage, a transversely extending rod, a shift lever held to said rod and connected at its inner end to elevate the carriage, a second lever having a pivoted connection on said rod and provided with a loose connection with the first-mentioned lever to have a limited movement independent of said first-mentioned lever, a support provided with an opening, a stop pivotally held to said support and adapted to be engaged by the end of said second lever and adapted to be moved thereby to close the opening in the support, means carried by the first-mentioned lever and adapted to enter the opening when the first-mentioned lever is depressed, and means for locking the carriage in either of its elevated positions. 100
17. In a typewriting machine, the combination of a carriage, a transversely extending rod, a shift lever rigidly held to said rod and connected at its inner end to move the carriage, a second lever pivotally held to said rod and having a loose connection with the first-mentioned lever to have a limited movement independent thereof, and a stop adapted to be operated by said second lever to engage a part carried by the first-mentioned lever to limit the movement of said latter lever. 110
18. In a typewriting machine, the combination of a carriage, a transversely extending rod, a shift lever held to said rod and connected at its inner end to move the carriage, a second lever pivotally held to said rod and having a pin-and-slot connection with the first-mentioned lever to have a limited movement independent thereof, and a horizontally movable stop adapted to be operated by said second lever to engage a part carried by the first-mentioned lever to limit the movement of said latter lever. 120
16. In a typewriting machine, the combination of a carriage, a pair of shift levers having independent operating means adapted to move the carriage to different elevated positions, a movable and pivoted stop actuated by one of the levers only and adapted to limit its movement and consequently the shift of the carriage, and a spring tending to hold the stop against the action of said lever. 95
15. In a typewriting machine, the combination of a carriage, a pair of shift levers having independent operating means adapted to move the carriage to different elevated positions, a movable and pivoted stop actuated by one of the levers only and adapted to directly engage one of the levers to limit its movement and consequently the shift of the carriage, a spring tending to hold the stop against action of said lever, and means for locking the carriage in either of its elevated positions. 105
14. In a typewriting machine, the combination of a carriage, of a pair of shift levers adapted to move the carriage to different elevated positions, a bracket having an opening therein, a pin carried by one of the levers and adapted to enter said opening, and a horizontally movable stop adapted to be forced in position by one of said levers to close the opening and thereby limit the throw of said pin-carrying lever. 75
13. In a typewriting machine, the combination of a carriage, of a pair of shift levers adapted to move the carriage to different elevated positions, a bracket having an opening therein, a pin carried by one of the levers and adapted to enter said opening, a pivoted stop adapted to be forced in position by one of said levers to close the opening and thereby limit the throw of said pin-carrying lever. 85

either of said levers in its depressed position to lock the carriage elevated.

23. In a typewriting machine, the combination of a carriage, a transversely extending rotary rod, a shift lever held to said rod and connected at its inner end to elevate the carriage, a second lever having a connection with the first-mentioned lever to have a limited movement independent of said first-mentioned lever, a support, a stop pivotally held to said support and adapted to be engaged by the said second lever to be moved thereby, a spring tending normally to force the stop against the action of the lever, means carried by the first-mentioned lever and adapted to engage the stop when the second lever is depressed, and means for locking either of said levers in its depressed position to lock the carriage elevated.

24. In a typewriting machine, the combination with a carriage, of two shift levers adapted to move the carriage to different elevated positions, a bracket, a laterally movable stop held to said bracket and adapted to be operated by one of said levers, a pin mounted upon the inner end of one of said levers and adapted to be engaged by the stop when the stop is moved by the other of said levers, and nuts for adjustably holding said pin.

25. In a typewriting machine, the combination with a carriage, of two shift levers located at the same side of the machine and adapted to move the carriage to different elevated positions, a bracket, a laterally movable pivoted stop held to said bracket, a spring normally forcing the stop in one direction, said stop being adapted to be operated by one of said levers, a device mounted upon the inner end of one of said levers and adapted to be engaged by the stop when the stop is moved by the other of said levers, and means for adjustably holding said device.

26. In a typewriting machine, the combination of a carriage, a transversely extending rod, a shift lever held to rock said rod, a second shift lever pivotally held to the rod and having a positive yet loose connection with the first-mentioned lever, said first-mentioned lever being connected at its inner end to elevate the carriage, means independent of said levers and operated by one of the levers whereby the movement of the first-mentioned lever may be limited, and a spring tending normally to elevate the carriage.

27. In a typewriting machine, the combination of a carriage, a transversely extending rocking rod, a shift lever held to rock said rod, a second shift lever pivotally held to the rod and having a loose connection with the first-mentioned lever, said first-mentioned lever being connected at its inner end to elevate the carriage, means op-

erated by one of the levers whereby the movement of the first-mentioned lever may be limited, a spring connected to the rod and tending normally to elevate the carriage, and means for varying the tension of said spring.

28. In a typewriting machine, the combination of a carriage, a transversely extending rod, a shift lever held to rock said rod, a second shift lever pivotally held to the rod and having a loose connection with the first-mentioned lever, said first-mentioned lever being connected at its inner end to elevate the carriage, a laterally movable stop operated by one of the levers whereby the movement of the first-mentioned lever may be limited, and a spring held to the rod at one end and to the machine frame at the other end tending normally to elevate the carriage.

29. In a visible typewriting machine, the combination of a platen carriage, a support for the platen carriage, a shift lever pivotally held at one side of the machine and connected at its inner end to move the support and elevate the carriage, a second lever pivotally held at the same side of the machine and adjacent to the first-mentioned lever and having a limited movement with respect to the first mentioned lever and independent thereof, a movable stop adapted to be operated by said second lever with a cam action to determine the extent of one shift movement of the carriage, means movable by the shift levers and adapted to engage the stop, and an arm pivotally held at the side of the machine opposite the shift levers and connected to the support and operated by both of the shift levers.

30. In a visible typewriting machine, the combination of a platen carriage, a shift lever pivotally held at one side of the machine and connected to elevate said carriage, a second lever pivotally held at the same side of the machine and adjacent to the first-mentioned lever, a pivoted stop element adapted to be moved on its pivot by said second lever only to determine the extent of one shift movement of the carriage, and means movable vertically as the carriage is elevated adapted to engage said stop element.

31. In a typewriting machine, the combination of a platen carriage, a support for the platen carriage, a shift lever pivotally held at one side of the machine, a second lever pivotally held at the same side of the machine and adjacent to the first-mentioned lever, vertically and bodily movable means located at opposite sides of the machine and connected to the support, said bodily movable means being moved on the depression of either shift lever to elevate the carriage, a pivotally held stop element adapted to be operated by said second lever to determine

the extent of one shift movement of the carriage, and an arm connected to the support and pivotally held at the side of the machine opposite the shift levers and moved 5 by both of the shift levers.

32. In a typewriting machine, the combination with a carriage, of a pair of shift levers having independent operating keys located on the same side of the machine and 10 adapted to move the carriage to different elevated positions, a movable and pivoted stop independent of said levers and operated by one of the levers only to limit the vertical movement of the carriage by said lever, 15 and means for locking the shift mechanism in either of the shift positions of the carriage.

33. In a typewriting machine, the combination with a support, of a platen mounted 20 on the support, shift levers connected to move the platen, means for limiting the shift movement of the levers and support, each shift-lever having a recessed portion, and a single lock lever having means adapted 25 to engage said recesses to lock either lever in its shifted position.

34. In a typewriting machine, the combination with a support, of a platen mounted 30 on the support, shift levers connected to move the platen, means for limiting the shift movement of the platen and support, each shift-lever having a recessed portion on the under edge thereof, and a single lock lever having spaced projecting parts adapt-

ed to engage said recesses to lock either lever 35 in its shifted movement.

35. In a typewriting machine, the combination of a frame, a movable support, two shift levers having relatively different movements for adjusting the support to different 40 degrees, the said levers being arranged in close relation and pivotally held adjacent to one side of the frame, and a pivoted arm adapted to limit the shifting movements of the support according to the position of 45 said arm.

36. In a typewriting machine, the combination of a movable support, two relatively movable levers located adjacent to each other and so connected as to have independent movements, and a single element having different positions and actuated by one lever only whereby the levers may shift the support different distances.

37. In a typewriting machine, the combination of a vertically movable support, two relatively movable levers located adjacent to each other and having a pin-and-slot connection so as to have independent movements, and single pivoted means whereby 60 the levers may shift the support to different distances.

This specification signed and witnessed this 4th day of June A. D. 1909. 65
